UNITED STATES PATENT OFFICE

GEORGE PETRAK, OF QUINCY, WASHINGTON

OIL CAN

Application filed May 19, 1928. Serial No. 279,094.

This invention relates to improvements in oil cans.

The principal object of this invention is to produce an oil can wherein the oil will be delivered to the spout, irrespective of the position in which the can may be placed.

Another object is to provide means whereby the oil may be forcibly ejected from the can.

Another object is to produce a device which conforms to the standard practice and construction of oil cans.

A further object is to provide a can which is simple and therefore economical to manufacture.

Other objects and advantages will be apparent during the course of the following description.

In the accompanying drawings forming a part of this specification, and in which like numerals are employed to designate like parts throughout the same,

Figure I is a vertical cross-section of my device, and

Figure II is an enlarged detail cross-section taken on the line 2—2 of Figure I.

The ordinary oil can merely consists in a can having a spout secured thereon. This type of can will not deliver oil upwardly and there are many positions into which the can must be placed where the oil will not be ejected therefrom, as for instance, many parts beneath the body of the motor vehicle.

I have therefore produced an oil can wherein all of the oil may be ejected therefrom, irrespective of its position.

In the accompanying drawings wherein for the purpose of illustration is shown a preferred embodiment of my invention, the numeral 5 designates the ordinary body of a can having a flat bottom 6 and an upstanding ring 7, to which the spout 8 is connected by a flat collar 9. The spout 8 carries an offset projection 11, within which a piston 12 is adapted to move.

This piston is contacted by a rod 13 and a thumb piece 14. A spring 16 serves to normally hold the piston in the position herein shown. A valve 17 is interposed between the

piston and the upper extremity of the spout, and is seated by means of a spring 18.

Extending into the can 5 is a downwardly inclined pipe 19 having a T-head 21, into which is rotatably mounted the bent end of a feed pipe 22. This feed pipe may carry a strainer in its lower end if desired, and is rotatably held in the T-head 21 through the medium of a cap 23 and an annular ring 24.

A valve as shown at 26 is normally seated by a spring 27. Openings 28 in the bent end permit a flow of oil from the pipe 22 to the pipe 19.

The result of this construction is that the pipe 22 may swing from the full line position of Figure I, to the dotted line position of the same figure. A pin 29 acts as a stop so as to prevent the swinging pipe from contacting with the bottom or top of the can.

In operation, the pump is actuated through the medium of the thumb piece 14, with the result that oil is taken from the can through the pipe 22, past the valve 26, thence into pipe 19 on the suction stroke. On the pressure stroke, this oil which is trapped above the valve 26, is forced upon the valve 17 and discharged through the spout 8. On the return or suction stroke of the pump, the valve 17 remains closed.

It will thus be seen that I have provided a very simple means for accomplishing all of the objects herein set forth.

It is to be understood that the form of my invention herewith shown and described is to be taken as a preferred example of the same, and the various changes relative to the shape, size, material and arrangement of parts may be resorted to without departing from the spirit of the invention, or the scope of the subjoined claim.

Having thus described my invention, I claim:

In an oil can, a receptacle, a spout secured to said receptacle, a pipe extending downwardly from said spout into said receptacle and angularly disposed with respect to the spout, a T member horizontally positioned on the end of said pipe, a delivery pipe hingedly mounted in the T portion of said first mentioned pipe, a valve positioned in

said delivery pipe, a valve positioned in said spout, a pump secured to said spout at a point between said valves, means for limiting the rotation of said delivery pipe about its hinged connection so that said pipe will not contact said receptacle.

In testimony whereof I affix my signature.
GEORGE PETRAK.
